(57) **CLAIM**

The ornamental design for a bag, as shown and described.

DESCRIPTION

FIG. 1 is a perspective view of a bag in a first configuration. FIG. 2 is a front view of the bag of FIG. 1. FIG. 3 is a rear view of the bag of FIG. 1. FIG. 4 is a left side view of the bag of FIG. 1. FIG. 5 is a right side view of the bag of FIG. 1. FIG. 6 is a top view of the bag of FIG. 1. FIG. 7 is a bottom view of the bag of FIG. 1. FIG. 8 is a perspective view of the bag of FIG. 1 in an expanded, second configuration.

FIG. 9 is a front view of the bag of FIG. 8.

FIG. 10 is a rear view of the bag of FIG. 8.

FIG. 11 is a left side view of the bag of FIG. 8.

FIG. 12 is a right side view of the bag of FIG. 8.

FIG. 13 is a top view of the bag of FIG. 8; and,

FIG. 14 is a bottom view of the bag of FIG. 8.

The broken lines in the figures illustrate portions of a bag and form no part of the claim.
